UNITED STATES PATENT OFFICE.

JAMES P. GARDNER, OF CHICAGO, ILLINOIS, ASSIGNOR TO THE REDUCING MACHINE COMPANY, A CORPORATION OF ILLINOIS.

BODY-TREATMENT MACHINE.

1,134,084.

Specification of Letters Patent. Patented Mar. 30, 1915.

Application filed December 31, 1913. Serial No. 809,598.

To all whom it may concern:

Be it known that I, JAMES P. GARDNER, a citizen of the United States, residing at Chicago, in the county of Cook and State 5 of Illinois, have invented certain new and useful Improvements in Body-Treatment Machines, of which the following is a specification.

This invention relates more particularly 10 to a machine or apparatus which is intended to be used for treating or acting upon persons in order to secure certain results, such as reduction in size, reduction in weight, reducing or overcoming muscular ailments, 15 stimulating the action of internal organs and the like.

The objects of the present invention are 20 to provide a machine or apparatus whereby the body of a person may be subjected to any desired degree of pressure and be simultaneously rolled or acted upon by the members in contact therewith; to provide a simple and efficient machine for rolling and 25 pressing or massaging the body or limbs of a person; and in general to provide a machine for giving such treatment as will be more fully described and explained herein-after.

In the accompanying drawings illustrating 30 my invention: Figure 1 is a side elevation of the machine with the swinging or pressure arms shown in extended or open position; Fig. 2 is a rear view of the same; Fig. 3 is a plan view; Fig. 4 is a view similar to Fig. 3, but with the arms shown in the position which they may assume when the machine is acting upon the body of a person; Fig. 5 is a sectional plan view illustrating certain features of the driving and 40 adjusting mechanism; Fig. 6 is a detail of the adjustable stand; and, Fig. 7 is a detail of the roller brackets.

In all of these figures the machine is 45 shown more or less diagrammatically, parts being broken away or omitted for convenience in illustration.

The basic feature or principle of my invention consists in the provision of rotatable or movable members which are pressed with 50 any degree of pressure desired, against the trunk or limbs of a person, and then rolled or moved while in such pressing engagement, such members preferably making contact or engaging as nearly as possible

around the entire circumference of the 55 trunk or limbs being acted upon.

The illustrations in the accompanying drawings show a particular form of machine embodying this principle and other particular features of my invention. As 60 shown in these drawings, 10 indicates the base of the machine to which is secured the rear frame members 11. The upper and lower horizontal frame members 12 and 13 at the top of the machine are provided with 65 rearwardly extending projections 14 and 15, which are secured to the vertical members 11. The frame members 12 and 13 are approximately semi-circular, as indicated in Figs. 3 and 4, and are supported at their 70 front ends by the vertical shafts 16 and 17. The lower ends of these shafts engage with bearings 18 and 19 on the base 10, and are provided with worm gears 20 and 21. A horizontal shaft 22 is mounted in projections 23 and 24 from the bearings 18 and 19, and is provided with worms 25 and 26, which engage with the worm gears 20 and 21. This shaft is provided with means, such as the cranks 27, for turning the same, the 75 arrangement being such that when the crank is turned, the worms and worm gears will cause the shafts 16 and 17 to rotate. Arms 29 and 30 are secured to the shafts 16 and 17, between the frame members 12 and 13, 80 so that they will swing when the shafts are turned. Short shafts 31 and 32 are mounted in the outer ends of the arms 29 and 30. The shaft 31 is provided at its upper and lower ends with sprockets 33, and the shaft 90 32 is provided with corresponding sprockets 34.

A pair of driving shafts 35 and 36 have 85 their lower ends engaging with bearings 37 and 38 secured to the base of the machine, 95 and extend up through bearings 39 and 40 in the frame members 12 and 13. These shafts are provided at their lower ends with worm gears 41 and 42 which are both engaged by a worm 43 which is secured to a 100 shaft 44. This shaft is mounted in bearings 45 and is driven by means of a motor 46 or in any other desired manner. The upper end of the shaft 35 is provided with two driving sprockets 47, and the upper end of 105 the shaft 36 is provided with two corresponding sprockets 48.

The shaft 16 is provided at its upper end

with two sprockets 49 which are respectively in horizontal alinement with the upper and lower sprockets 33 on the shaft 31 and the upper and lower sprockets 47 on the shaft 35; and the shaft 17 is provided at its upper end with two sprockets 50, which are respectively in alinement with the upper and lower sprockets 34 on the shaft 32 and the upper and lower sprockets 48 on the shaft 46.

10 Two arms 51 and 52 are pivotally mounted at the back of the machine upon bearings which are preferably concentric with the shafts 35 and 36. The arm 51 is formed of upper and lower horizontal members connected at their outer ends by a shaft 53 carrying the upper and lower sprockets 54. The arm 52 has a shaft 55 at its outer end which is provided with upper and lower sprocket 56. A chain 57 passes around the upper set of sprockets 47, 54, 49 and 33, and a second chain 58 passes around the corresponding lower set of sprockets. Similar chains 59 and 60 pass around the upper and lower sets of sprockets on the opposite side 25 of the machine, as will be clearly seen from the drawings. These pairs of chains 57, 58 and 59, 60 carry the devices which act directly upon the body. Various devices may be used to be applied to the body, but in 30 the drawings these devices are shown as comprising series of rollers 61 which are rotatably supported on the chains. In order to carry these rollers, the chains are provided at intervals with vertical brackets 62 35 which are securely fastened to the chains and have end bearings for the rods 63 upon which the rollers 61 are mounted. These rollers may be made of any suitable material, but good results are obtained from 40 rollers made of unyielding material such as wood or the like. In the machines constructed, I have found that rollers approximately 18 inches long and 1½ inches in diameter give satisfactory results.

45 A stand 64 is secured to the base 10, in the center of the machine, and is threaded at the top to receive a screw 65 which carries the platform 66. This provides for a convenient method of adjusting the platform 50 for persons of different heights and when the platform is adjusted, it may be locked in position by means of a locking screw 67 which clamps the upper portion of the stand 64 against the screw 65.

55 It will be observed that when the arms 29 and 30 are swung inwardly, the chains would be loosened if some means for tightening the same were not provided. The arms 51 and 52 with the sprocket wheels carried thereby, act as tighteners for the chain belts, suitable means being provided for placing tension on these arms. A rope or cable 68 is attached to the upper and outer end of the arm 51 and then passes over a

guide pulley 69, carried by a bracket 70 at 65 the rear of the machine, and then down and under a traveling pulley 71 and up and over a second guide pulley 72, and has its opposite end secured to the outer and lower end of the arm 51. The guide pulley 72 is carried 70 on a bracket 73 at the rear of the machine. A corresponding rope or cable 74 is connected at one end to the upper outer portion of the arm 52 and then passes over a guide pulley 75 and then down and under a 75 traveling pulley 76 and up and over a second guide pulley 77 and has its other end connected to the outer and lower portion of the arm 52. The guide sheaves 75 and 77 are carried by brackets 78 and 79 at the rear 80 of the machine. The blocks of the pulleys 71 and 76 are connected by a rope or cable 80 which runs under a sheave or pulley 81 which carries a weight 82. This arrangement is such that the weight, acting through 85 the ropes and pulleys, tends to swing the outer ends of the arms 51 and 52 backwardly and the weight is preferably made only sufficiently heavy so that it will hold the chains from sagging and will prevent 90 their running off from the sprocket wheels. I also provide means so that any desired amount of tension may be placed upon the chains, such tension being regulated by or under the control of the operator. This is 95 done by providing means for forcibly pulling on the free ends of the arms 51 and 52. The arm 51 is provided with upper and lower ropes or cables 83 and 84, which cables are connected to the arms and pass 100 around drums 85 and 86 on a vertical shaft 87 at the rear of the machine. Corresponding cables 88 and 89 are connected to the arm 52 and wound around the same drums. The shaft 87 is provided with a spring 90 105 which tends to rotate it sufficiently to take up any slack in these cables. A worm wheel 91 is mounted to turn freely on the lower end of the shaft 87. This wheel is engaged by a worm 92 on a shaft 93 which extends 110 out to the side of the machine and is provided with a crank 94 for turning the same. The worm wheel 91 is provided with clutch teeth which engage with a clutch member 95 which is keyed or splined to the shaft 87, 115 and which may be shifted up or down by means of a lever 96, a spring 97 also being provided beneath the clutch member which tends to hold it in engaging position.

The operation of my improved machine 120 will be readily understood from the above description and the accompanying drawings. The person to be treated or acted upon, usually stands upon the stand or platform 66, as clearly shown in Fig. 1, and may face or stand in any desired position between the chains or rollers. Handles 98 are provided which may be grasped by the

person acted upon when standing in the position shown in Fig. 1. The motor may be started either before or after the person enters the machine. When the motor is started, it turns the worm 43 which in turn drives the worm gears 41 and 42 which rotate the shafts 35 and 36 and thus drive the sprocket wheels 47 and 48 which drive the roller supporting chains or carriers, all of the other sprocket wheels merely acting as guides. These chains may be driven at any desired speed, but I have found that good results are obtained when they are driven about twenty feet per minute.

When the treatment to be given is around the trunk of the person to be acted upon, he takes position on the platform 66 and the operator turns the crank 27 which rotates the shafts 16 and 17 and swings the arms 29 and 30 inwardly. As these arms swing in, the portions of the chains between the driving sprockets and the sprockets at the outer ends of the arms 51 and 52, will conform closely to the curvature of the body of the person and a considerable number of the rollers 61 will engage with the body as clearly indicated in Fig. 4, in which the dotted line 99 represents the outline of a person in the machine. When a person is standing in the position shown in Fig. 1, or standing facing the other way, pressure from front to back may be regulated by turning the crank 27 which will swing the arms in until the inner ends tend to press the person against the rollers at the back of the machine. In this manner, any desired pressure may be brought against the back or abdomen, while but slight tension is given to the chains, and consequently these portions of the body will be most thoroughly acted upon. If it is desired to give a uniform action or pressure around the body, the arms 29 and 30 will be swung in until the rollers engage with as much of the periphery of the body as possible, and then any desired amount of pressure may be secured upon the body by increasing the tension on the chains. This is done by throwing the clutch 95 into engagement with the worm wheel 91 and then turning the crank 94. When this crank is turned, the worm 92 turns the worm wheel 91 which drives the shaft 87 and causes the cables 83 and 88 to be wound upon the drum 85, and the cables 84 and 89 to be wound up on the drum 86. As these cables are wound up they pull the arms 51 and 52 backwardly as indicated in Fig. 4, and therefore tighten the chain belts. These belts with the contact or pressure rollers may be driven in any direction desired, or their direction of movement may be alternated as by reversing the motor, but I prefer to drive them in opposite directions or so that the inner portions there-

of move from the back of the machine toward the front as indicated by the arrows in Fig. 4. The rollers 61 are spaced at any desired distance apart, along the chains, but are preferably located sufficiently far apart so as to prevent a too continuous contact area, and so as to permit each roller to engage more or less forcibly with the body. These rollers, however, should be proportioned and mounted so as to prevent the chains from coming in contact with the body or body covering. The person taking the treatment, particularly a body treatment, ordinarily wears a gown of heavy material such as duck, in order to prevent the rollers from engaging directly with the skin. It will be seen that, with the chains wrapped substantially around the entire periphery of the body and with the rollers moving in opposite directions, there will be no noticeable tendency toward twisting the body while, at the same time, the rollers acting under such pressure as may be desired, will give a highly efficient massaging action. An important feature of this machine is the balanced action of the massaging devices, due to their being mounted on the flexible chains, so that the pressure of the rollers on one side of the body is resisted by the rollers on the opposite side of the body. On account of this balanced yielding support of the body between the massaging devices an exceedingly heavy pressure may be safely given, which gives a thorough kneading action to the body. In fact the pressure which may be safely applied is so great that the supporting chains must be strong and substantial in order to withstand the strains. The entire machine must be made very strong in order that this pressure may be given thereby. This will be further understood from the fact that I have found it desirable to use $\frac{1}{2}$ horse-power motors for driving the chains. When the treatment has been continued for a sufficient length of time, the stress put upon the arms 51 and 52 by the tightening cables is relieved and the clutch 95 thrown out of engagement which leaves merely the weight 82 to act upon the belt tighteners. The crank 27 is then turned to swing the arms 29 and 30 outwardly, which permits the person being acted upon to step out of the machine.

This machine may be used in a large variety of ways for giving treatment to the different portions of the body. For instance, in some cases the person to be acted upon sits upon a stool facing forwardly in the machine with the rollers engaging with, or embracing the back and shoulders or the upper portion of the body. Or the person to be acted upon may stand sidewise in the machine, or in any desired position whereby

the rollers may best engage with the portion of the body, which is desired to be treated, and the swinging arms 29 and 30 with the auxiliary chain tightening devices provide 5 means for regulating the machine for acting upon such different portions of the body with any desired degree of pressure. For 10 massaging, or acting upon a person's arm, the arms 29 and 30 may be swung inwardly until their inner ends bring the opposite 15 rollers close together, and the arm can be inserted from the front of the machine and will be engaged for practically its entire length by the rollers on either side thereof, which will give an exceedingly rapid and 20 effective treatment. It is difficult, or impossible to determine all the benefits which may result from the proper use of this machine, but in actual tests it has been proven 25 effective in reducing the sizes of corpulent persons, that is in reducing their various circumferential measurements, as well as reducing the weights of such persons, and has also served for the purpose of reducing 30 lameness or soreness in the limbs due to strains or the like. The machine also seems to stimulate the action on the internal organs in a desirable manner.

It will be observed that various forms of 35 rollers may be used in my machine, and various changes may be made in the details of construction and arrangement of parts without departing from the spirit of this invention, and therefore, I do not wish to 40 limit myself to such exact construction and arrangement, except as specified in the following claims; in which I claim:

1. In a machine of the character set forth, the combination of a series of massaging 45 rollers for engagement with the body of a person, flexible supports for said rollers, said supports being spaced a sufficient distance from the engaging portions of the rollers so as not to come in contact with the 50 body, means for holding said rollers in engagement with the body, and means for moving said rollers while in engagement with the body.

2. In a machine of the character set forth, 55 the combination of a continuous series of rotatable devices for engagement with the body of a person, flexible supports for said devices arranged to avoid contact with the body, means for actuating said supports to roll the devices against the body, and means for tightening said supports to regulate the pressure against the body.

3. In a machine of the character set forth, 60 the combination of two series of oppositely disposed rotatable devices for engagement with the body of a person, flexible carriers for carrying the engaging devices of each of said series, means for adjusting said carriers to bring a plurality of the engaging

devices of each series into engagement with the body, and means for actuating said carriers.

4. In a machine of the character set forth, the combination of a pair of oppositely disposed flexible carriers, a series of rollers secured to each of said carriers and spaced sufficiently close to prevent the carriers from coming in contact with the person acted upon, means for supporting said carriers, means for driving said carriers, and means for adjusting the tension on said carriers.

5. In a machine of the character set forth, the combination of a pair of oppositely disposed flexible carriers, a plurality of rollers 70 rotatably supported on each of said carriers, said carriers being arranged so that the rollers of the respective carriers may engage with the opposite sides of the body or limbs of a person placed between the carriers, 75 means for driving said carriers, and means for adjusting the tension on the carriers whereby the pressure on the body or limb placed between the rollers may be regulated.

6. In a machine of the character set forth, 80 the combination of a frame, a pair of driving shafts mounted in said frame, means for turning said shafts, oppositely disposed, adjustable chain supports mounted in said frame, two chains carried by each of said 85 supports, means for driving said chains from the driving shafts, a plurality of rollers mounted on said chains, means for adjusting said chain supports whereby the oppositely disposed rollers may be brought 90 between the supports, means for tightening said chains to hold them in position, and auxiliary means for giving additional tension to the chains.

7. The combination of a frame, a pair of drive shafts mounted in the back of said frame, means for turning said shafts, a pair of arm supporting shafts mounted in the frame at the front thereof, means for manually turning said shafts and holding them in adjusted position, inwardly projecting arms carried by said shafts, a pair of chain tightening arms pivotally mounted at the back of the machine, driving sprockets 110 mounted on the drive shafts, guide sprockets carried by the arm supporting shafts, and also by the front and rear arms, two chains carried by said sprockets on each side of the machine, vertically arranged brackets 115 carried by the chains on each side of the machine, rollers carried by said brackets, means for putting a fixed tension on the rear arms, manually controlled means for placing an additional tension on said arms, 120 and a stand or the like at the center of the machine for supporting a person between the oppositely disposed pairs of chains, the

arrangement being such that the forward arms may be adjusted to cause the rollers on either side of the person to engage with the body, and the tension on the chains may be adjusted to regulate the pressure of the rollers against the body.

8. The combination of a frame, a pair of drive shafts arranged adjacent to each other at the back of the frame, a second pair of shafts mounted in said frame at the sides thereof and in front of the drive shafts, worm gears secured to said last named shafts, a shaft mounted adjacent to the worm gears, worms on said last named shaft engaging with the worm gears, means for turning said last named shaft, inwardly extending arms secured to said second named shafts, chain tightener arms pivotally mounted at the back of the machine, drive sprockets on said drive shafts, guide sprockets on said second named shafts and also on the front and rear arms, two chains carried by said sprockets on either side of the machine, brackets carried by said chains, body engaging devices carried by said brackets, cables secured to the chain tightening arms at the back of the machine, guide pulleys for said cables, a weight connected with said cables, a shaft mounted at the back of the machine, drums on said shaft, cables from said chain tightening arms to said drums, and means for manually turning said last named shaft for tightening the last named cables.

9. In a machine of the character set forth, the combination of a pair of horizontally arranged belts, a second pair of belts disposed oppositely to the first-named pair, vertical brackets secured to the respective pairs of belts, rollers mounted in said brackets, the rollers on the opposite pairs of belts being adapted to engage with the opposite sides of the body of a person, means for driving said belts, and adjusting means for causing the rollers of the opposite pairs to approach and recede from each other for adjusting the pressure of the rollers against the body of the person acted upon.

10. In a machine of the character set forth, the combination of two oppositely disposed flexible roller carrying devices, the rollers of which are adapted to engage with the opposite sides of the body of a person, adjusting means for causing portions of said roller carrying devices to approach toward and recede from each other, means for driving said roller carrying devices and means for adjusting the pressure of the rollers against the body of the person acted upon.

11. In a body treatment machine, the combination of a frame, an adjustable stand in the center of the machine at the front thereof, two shafts mounted in the sides of the

frame at the front of the machine, means for turning said shafts and locking them in adjusted position, inwardly extending arms secured to said shafts, upper and lower sprockets carried at the outer ends of each of said arms, upper and lower sprockets on each of said shafts in alignment with the sprockets of their respective arms, two drive shafts mounted adjacent to each other at the rear of the frame, upper and lower sprocket wheels on each of said shafts in alignment with the corresponding sprocket wheels on said arms, chain tightening arms pivotally mounted concentric with said drive shafts, upper and lower sprockets at the outer ends of said chain tightening arms, said sprockets being in alignment with the corresponding sprockets of the first named arms, chain belts around the upper and lower sprockets at both sides of the machine, body engaging devices secured to said chain belts, tension means for swinging said chain tightening arms for holding the chain belts in position, manually operated tension means for giving additional tension to said chain tightening arms, a motor, and gearing from the motor to the drive shafts.

12. In a massage machine, the combination of series of oppositely disposed vertically arranged rollers, horizontally arranged flexible yielding supports for said rollers, said supports being arranged so as not to come in contact with the person acted upon, means for moving said supports to cause the rollers to act on the body of a person positioned between the series of rollers, and means for adjusting said series of rollers relatively to each other, in a horizontal direction.

13. In a massage machine, the combination of two oppositely disposed series of vertically arranged rollers, the rollers in each series being spaced at short distances apart to prevent their supports from coming in contact with the body, horizontally arranged yielding supports for said rollers, means for moving said supports horizontally to cause the rollers to act upon the body of a person positioned between the two series of rollers, and means for adjusting the supports horizontally with respect to each other, in order to increase or decrease the distance between the rollers of the two series.

14. In a massage machine, the combination of a pair of horizontally arranged belts, means for moving said belts in a horizontal direction, and a plurality of vertically arranged rollers spaced at short distances apart and carried by said belts, and adapted to act upon the body of a person pressing against the same while preventing the belts from engaging with the body.

15. In a massage machine, the combination of a pair of horizontally arranged belts,

means for supporting said belts, means for reciprocating said belts in a horizontal direction, and a plurality of vertically arranged rollers spaced at short distances apart, and 5 carried by said belts.

16. In a massage machine, the combination of two oppositely disposed pairs of horizontally arranged flexible belts, vertically arranged rollers carried by each pair of

said belts, means for reciprocating each pair 10 of belts in a horizontal direction, and means for adjusting the pairs of belts horizontally to move them toward or away from each other.

JAMES P. GARDNER.
